BLANK FEEDING MECHANISM

Ronald E. J. Nordquist, Maplewood, N. J., assignor to American Can Company, New York, N. Y., a corporation of New Jersey

Application November 17, 1942, Serial No. 465,873

9 Claims. (Cl. 271—10)

The present invention relates to a blank feeding mechanism and has particular reference to feeding narrow strips of sheet material at high speeds to can making machines.

An object of the invention is the provision of a blank feed mechanism for a can making machine wherein blanks are fed in rapid succession from a stack of such blanks by a short stroke feed finger acting against the blanks in a fashion which pivotally swings them from the stack into the grip of high speed rotating feed rollers for advancement in a quiet, highly efficient manner which is conducive to the operation of high speed production machines.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a blank feeding mechanism embodying the instant invention, with parts broken away and parts shown in section and with a sheet metal blank in position in the mechanism;

Fig. 2 is a sectional detail taken substantially along the line 2—2 in Fig. 1;

Fig. 3 is a transverse sectional view taken substantially along the broken line 3—3 in Fig. 1, with parts broken away;

Fig. 4 is a longitudinal section taken substantially along the broken line 4—4 in Fig. 3, with parts broken away;

Fig. 5 is a sectional detail taken substantially along the line 5—5 in Fig. 4, with parts broken away;

Fig. 6 is an end elevation as viewed from the right in Fig. 1 and drawn to a reduced scale, with parts broken away;

Figs. 7 and 8 are plan and transverse sectional details taken substantially along the lines 7—7 in Fig. 3, and 8—8 in Fig. 4, with parts broken away;

Fig. 9 is a top plan view with parts broken back and parts shown in section and with parts omitted to clearly illustrate certain of the hidden working elements of the machine;

Fig. 10 is a transverse sectional detail taken substantially along the line 10—10 in Fig. 1, with parts broken away;

Fig. 11 is a fragmentary plan view similar to Fig. 1 and showing a blank in a different position; and

Figs. 12 and 13 are transverse sectional details taken substantially along the lower part of the

line section 3—3 in Fig. 1 and illustrating different positions of certain movable parts of the mechanism and showing a blank being fed from a stack during the feeding operation.

As a preferred embodiment of the invention the drawings illustrate a blank feeding mechanism for feeding narrow strips or blanks A of sheet metal along a predetermined path of travel. Annular collar bands are made from these strips and subsequently are inserted into metal cans of the tearing strip type in which the collar band is utilized as a seat for the cover when the latter is used as a reclosure.

The mechanism embodying the present invention is utilized preferably in conjunction with a more elaborate machine, such for example as a machine for forming the collar bands mentioned above. Such a collar band forming machine is disclosed in United States Patent 1,917,270, issued 20 July 11, 1933, to J. F. Peters and is entitled Machine for forming metal bands.

In the instant mechanism the strip blanks A are fed individually from the bottom of a stack of such blanks located within a magazine C (Figs. 25 1 and 3). This feeding of a strip is effected by shifting the forward end of each strip laterally while retaining its opposite end within the stack.

Such shifting of the strip removes its forward end from the magazine and places it in between a pair of separated and rotating high speed feed rollers D (Figs. 1 and 4). The lateral distance the forward end of the strip is shifted is equal substantially to the width of the strip. Hence since the strips are usually narrow this same distance is covered rapidly and with only a slight movement of the strip.

When the leading end of the strip is once located between the feed rollers D, the latter are brought into frictional engagement with the strip and thereupon withdraw it entirely from the magazine and advance it into the machine proper. This completes the feeding of the strip in a quick and efficient manner best adapted to high speed production machines.

The strip blank magazine C includes two pairs of lower and upper guide rails 21, 22 (Figs. 1, 2 and 3). One of the lower guide rails is disposed adjacent the feed rollers D. For this particular size and shape of strip blank one upper rail is

50 directly above one lower rail and the other upper rail is intermediate the two lower rails. At the bottom of the magazine the lower and upper rails have spaced and parallel vertical faces 23, 24 (see also Fig. 10) between which the narrow strips A in the bottom of the magazine are retained in

stacked order and in a horizontal position one on top of the other. The vertical faces 23, 24 of the rails merge into outwardly curved and inclined faces, the lower rail having an upper face 25 and the upper rail having an under face 26.

The curved and inclined faces 25, 26 support and retain a supply of strips A on edge and provide for fanning the strips into a horizontal position as they move by gravity around the curved faces and fall onto the stack retained between the vertical faces 23, 24. Two upright end plates 27 (Figs. 3, 6 and 11) secured on opposite sides of the lower guide rails 21 retain the strips in the upper portion of the magazine against endwise displacement. This is a usual magazine construction and is disclosed in the above mentioned Peters patent.

The lower guide rails 21 are mounted on a housing cover 28 (Figs. 1 and 3) of a main housing 29 which carries most of the parts of the feeding mechanism. The housing is bolted to a frame 30 (see also Fig. 4) which in the instant case is the main frame of the collar band making machine to which the feeding mechanism in this embodiment is attached. These lower guide rails are adjustable to accommodate different lengths of strip blanks and are secured in place by bolts 31 (Figs. 6 and 9), the heads of which are disposed in a T slot 32 in a support block 33 formed on the housing cover 28.

The upper guide rails 22 are mounted on an adjustable guide bracket 34 which is secured by bolts 35 to a spacer block 36 carried on top of the housing cover 28. Slots 37 in the guide bracket allow for its adjustment when the bolts 35 are loosened. The spacer block 36 may be held on the housing cover in the desired position by a similar slot 38 and bolt 39 connection.

The lower and upper guide rails 21, 22 thus mounted in the desired position on the housing cover 28 are on top of the rest of the mechanism. Considering the magazine from above it will be observed that the longitudinal feed line of the feed rollers D is at an angle to those strip blanks in the lower vertical part of the stack within the magazine. In this angular position the rear or outer ends of these lower strips in the stack are in the longitudinal feed line of the feed rollers D and are supported in this position on a horizontal foot 41 (Fig. 10) formed on the outer or rear upper guide rail 22.

The forward or inner ends of the vertical and angular stack of strips are disposed to one side of the feed rollers D. This end of the stack is supported on a foot extension 42 (see also Figs. 1, 9 and 11) of the inner or forward lower guide rail 21. The lowermost strip in the stack is always in a horizontal plane passing through the space between the two separated feed rollers D.

Intermediate its ends, the stack of strips A is supported on a foot 44 (Fig. 2) of the inner or forward upper guide rail 22. This middle part of the stack is engaged by a vibrator fork 45 (Figs. 3 and 9) mounted therebeneath. The prongs of the vibrator fork are formed on the free end of a horizontal arm 46 which is pivotally mounted on a pivot pin 47 carried in a pivot bracket 48 secured to the back of a depending guide member 49 bolted to the guide bracket 34.

The strip blanks A are fed from the stack at 70 the bottom of the magazine C. Every time a strip is removed from the stack, the vibrator fork 45 is rocked upwardly against the bottom of the stack. This raises the strips slightly and then lets them fall. This vibrates the strips in the 75

stack and thus facilitates their downward travel by gravity through the magazine.

Rocking of the vibrator fork 45 is brought about by an adjustable setscrew 52 (Figs. 3 and 9) which engages against a pad extension 53 of the vibrator arm 46. The screw is carried in the outer end of a support member 55 which is bolted to a rocker hub 56 mounted on a pivot shaft 57 carried in a pair of spaced bearings 58 formed in the housing 28.

The rocker hub 56 is formed with an actuating arm 59 which carries a cam roller 60 that operates against a face cam 62 (see also Figs. 1, 6 and 9) mounted on a drive shaft 63 journaled in bearings 64 formed in the main frame 30 of the collar band machine. The drive shaft 63 is continuously rotated in any suitable manner, preferably from a rotating element of the collar band machine, in time with the other moving parts of the machine.

Feeding of the lowermost strip blank A from the magazine C is brought about preferably by a short stroke, coin feed type reciprocating finger 71 (Figs. 1, 3, 12 and 13) which is located adjacent the outer edges of the strips in the magazine and near the center intermediate their ends. The feed end of this finger is formed with a flat nose 72 having a sharp feed step or shoulder 73 (Fig. 12) which is substantially equal to the thickness of one strip blank A. The feed step merges into a raised follower projection 74.

The opposite end of the feed finger 71 is formed with a pair of pivot trunnions 75 which are carried in a feed head 76 formed on the upper end of an upright rocker lever 77 disposed within the housing 29. Intermediate its ends the finger rests upon a vertical, yieldable button 78 which is carried in the feed head and which is backed up by a compression spring 79 housed within a clearance bore 81 formed in the head. A screw plug 82, threaded into the head keeps the spring and the button in place.

The spring 79 presses the button 78 against the feed finger 71 and thus holds the latter in an upward normal position against an overhanging stop extension 84 of the head, as shown in Figs. 3 and 13. In this normal position of the feed finger the feed step 73 of its nose 72 is in horizontal alignment with the outer edge of the lowermost strip A in the blank.

The rocker lever 77 which carries the feed finger 71, is mounted at its lower end on a pivot shaft 86 (Figs. 3 and 4) retained in a pair of spaced bearings 87 formed in an adjustable bracket 88. The bracket is keyed to and is slideable along an elongated boss 89 formed on the floor of the housing 29 so that the lever may be so placed as to keep the feed finger in a middle position relative to the particular length of strip. In other words, the mechanism is adjusted for each strip of different length. After such an adjustment the bracket may be locked in position by a bolt 91 which extends through a hole in the bracket and through an elongated slot in the floor of the housing.

The rocker lever 77 is rocked on its pivot shaft 86 by an edge cam 92 which operates against a cam roller 93 carried on a lug 94 formed on the lever. The cam roller is held in engagement with the cam by a tension spring 95. One end of the spring is secured to a lug 96 which extends inwardly from a wall of the housing 29. The opposite end of the spring is fastened to the outer end of an arm 97 which is formed on the rocker lever 77.

The cam 92 is keyed to a cam shaft 98 which is journaled at its ends in bearings 99 formed in the housing 29. The cam is also slideable along the shaft to bring it into alignment with the cam roller 93 when the lever 77 is adjusted for different lengths of strips A. A setscrew 101 is carried in the hub of the cam for locking the latter in place on the shaft after an adjustment.

The cam shaft 98 is continuously rotated in time with the other moving parts of the mechanism and of the collar band machine to which it is attached, by a sprocket 105 (Fig. 4) which is mounted on the cam shaft. This sprocket is driven by a chain 106 (see also Fig. 6) which operates over a driving sprocket 107 mounted on a shaft 108 journaled in bearing brackets 109 secured to an outer wall of the housing 29. The shaft 108 is rotated by a gear 111 which is mounted thereon and which meshes with and is driven by a gear 112 mounted on the drive shaft 63.

With such a construction of parts a short stroke is imparted to the rocker lever 77 in a quiet and highly efficient manner which is particularly adaptable to high speeds. This rocking of the lever reciprocates the rocker head 76, through a forward stroke and thence through a return stroke relative to the stack of strip blanks A in the magazine C.

On a forward stroke of the rocker head 76, the nose 72 of the feed finger 71 passes under the lowermost strip blank A in the stack while the feed step 73 engages the outer edge of the blank and pushes the blank laterally from the bottom of the stack (see Fig. 12). During this lateral feeding of the blank, the follower projection 74 on the finger engages under the stack of blanks raising the stack slightly. This relieves the pressure on the lowermost blank being fed so that the blank will not be dragged against the surface of the blank above. This prevents scratching of the blanks which is a very serious problem in feeding blanks which have been lithographed or otherwise coated. The inner edges of the blanks in the stack above the lowermost blank are backed up during this feeding operation by a guide face 114 formed on the adjustable guide member 49.

Such a lateral pressure applied to the blank intermediate its length incidental to its being fed from the magazine, pivots the blank at its outer end while moving it further at its inner end, that is, from the position shown in Fig. 1 to that shown in Fig. 11. During this shifting movement, the rear or outer end of the blank is held between the guide faces 23, 24 of the two outer guide rails 21, 22, the forward end of the blank being swung inwardly into position in alignment with and in between the open or spaced feed rollers D.

This swinging of the blank takes place through clearance slots 118, 119 (Figs. 2 and 13) formed in the inner upper guide rail 22 and in the guide member 49. The slot 118 in the guide rail 22 is located adjacent its stack supporting foot 44 while the slot in the guide member 49 is disposed adjacent a pair of such feet 121 (Figs. 1, 11 and 13) formed on the member.

After such a forward or feeding stroke, the rocker lever 77 immediately moves back through a return stroke in readiness to feed the next strip blank from the magazine. With such a short stroke rocker lever, this feeding takes place rapidly.

While the rocker lever 77 is moving back through a return stroke, the forward end of the

strip which has been shifted into place between or into the bight of the feed rollers D is gripped by the rollers and is fully and quickly withdrawn from the magazine and advanced into the collar band machine. The feed rollers D include an upper drive roller 135 (Figs. 4 and 8) and a lower pressure roller 136.

The upper roller 135 is formed on the inner end of a shaft 138 which is journaled in a long bearing 139 of a movable bracket 141. This bracket is mounted on a pivot pin 142 (see also Fig. 1) carried in a lug 143 which projects up from an extension 144 (Fig. 4) of the housing cover plate 28. This construction of roller mounting is provided so that the roller bracket may be lifted to move the roller into an inoperative position in case a strip becomes jammed between the rollers.

When the drive roller 135 is in its normal operating position it is held in place by a yieldable latch 147 which is mounted on a pivot screw 148 threadedly engaged in the extension 144 of the housing cover plate 28. The screw is surrounded by a compression spring 149 which is located in a recess 151 formed in the latch and which is interposed between the bottom of the recess and a washer 152 carried on the screw.

The latch 147 extends over the top of the bearing 139 and presses against a boss formed on the bearing. Two side lugs 154 which extend out from the bearing rest on the extension 144 of the housing plate 28 and thus locate the bearing and the roller in the proper operating position.

The upper drive roller 135 is continuously rotated (in a clockwise direction as viewed in Fig. 4) at high speed by a pulley 156 (Figs. 1 and 3) which is mounted on the outer end of the roller drive shaft 138. This pulley is driven by an endless belt 157 which operates over a drive pulley 158 (Fig. 6) mounted on the rotor shaft of an electric motor 159. The motor is supported on a bracket 161 which is bolted to a side of the housing 29.

The lower pressure roller 136 rotates on a short shaft or stud 165 (Figs. 4, 8 and 9) which is carried in a bearing 166 formed on a lever arm 167 which projects outwardly from the stack vibrator or rocker hub 56. This idler roller is raised and lowered relative to the upper or drive roller 135 in time with the feeding of a strip blank A from the stack. This raising and lowering of the pressure roller is effected in part by the cam roller 61 that operates against the face cam 62. This is brought about simultaneously with the vibrating of the strip blanks in the magazine C.

The cam roller 61 is held against the cam 62 by a compression spring 171 (Fig. 4) which surrounds a bolt 172 loosely held with a yoke 173 (see also Fig. 5) formed on a lug 174 of the machine frame 30. The spring is interposed between the yoke and a round or button shaped head 175 formed on the top of the bolt. This head is pressed upwardly by the spring against a seat 176 formed in a lug extension 177 of the lower roller lever arm 167. As previously stated, it is this spring that holds the cam roller 61 against the face cam 62 and with the cam effects the vertical oscillation or movement of the roller above mentioned.

The normal position of the pressure roller 136 is separated from and in spaced relation to the upper or drive roller 135. When a strip blank A comes into position between the rollers, the face cam 62 allows the compression spring 171 to rock the lever arm 167 upwardly and thus to force the pressure roller and the interposed strip blank

against the rotating drive roller. The strip thus held in frictional engagement with the drive roller is propelled forward (toward the left as viewed in Fig. 4). This completely withdraws the strip from the stack and feeds it toward the collar band making machine.

During this advancement, the strip is guided by a short stationary guide block 181 (Figs. 1 and 4) which is secured to a bracket 182 bolted to the top of the machine frame 30. Machine feed rollers 185, 186 mounted on respective shafts 187, 188 journaled in bearings 189 formed in the bracket 182, pick the strip up as it leaves the guide block 181 and advance it into the collar band machine proper.

These machine feed rollers 185, 186 are rotated in time with the feed rollers 135, 136 in any suitable manner, preferably from some element of the collar band making machine. By way of example, the machine feed rollers may be rotated in unison by a pair of meshing gears 191, one of these gears being driven by a gear 192 of the collar band machine.

Provision is made for stopping the feeding of the strip blanks A from the magazine C without stopping the operation of the mechanism if for any reason the collar band machine cannot receive them. This is brought about by a stop latch 201 (Figs. 3 and 7) which operates against a lug 202 formed on a side of the rocker lever arm 97. This stop latch is mounted on a pivot pin 203 carried in an upright extension 204 of the rocker lever bracket 88. An arm 205 projecting outwardly from the stop latch bears against the top end of a vertically disposed core 206 of an electric solenoid 207 secured to and movable with the bracket 88. This solenoid is connected by wires 209 to a suitable source of electric energy and to the various electric stop devices which are usual in a collar band making machine as disclosed in the above mentioned Peters patent.

The solenoid 207 is maintained normally in a deenergized condition. In this condition a spring 211 housed within the solenoid presses upwardly on its core 206 and the latch arm 205 and thus holds the latch 201 out of the path of travel of the lug 202 on the rocker lever arm 97. This spring 211 is balanced in its normal holding action by a flat spring 212 which is secured to the upright extension 204 and which engages the latch.

Thus when the collar band machine is operating under normal conditions, the stop latch 201 is held in an inoperative position and normal feeding of the strip blanks A from the magazine C takes place. If, however, one of the electric stops in the collar band machine operates to indicate abnormal conditions, such as a jam or the like in the machine, the solenoid 207 is immediately energized by electric current then flowing through the solenoid circuit established by the stop circuit in a conventional manner.

Energizing of the solenoid 207 immediately draws the core 206 downwardly into the solenoid against the resistance of the spring 211. This permits the flat spring 212 to rock the latch 201 into the path of travel of the lug 202. The lug upon engaging the latch is held against further movement and the rocker lever cam roller 93 thereupon no longer follows the cam 92. The rocking movement of the lever 77 is thus temporarily stopped and thus feeding of strips A from the magazine ceases.

When the condition in the collar band machine is again brought to normal and the solenoid is

again deenergized, the stop latch 201 returns to its normal position. This frees the rocker lever 77 for normal feeding operation. The circuits connecting the solenoid with the various stop devices in the collar band are such as are usually incorporated in automatic machines and it is therefore thought that further detailed explanation of these circuits need not be given.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a high speed blank feeding mechanism for feeding narrow elongated strip blanks of sheet material, the combination of a support for opposite ends of a strip blank, a pair of high speed rotatable feed rollers adjacent one end of said support, and means for pivotally shifting said strip blank in its support about a point disposed substantially in the plane of the bight of the feed rollers to move the blank into between said rotating rollers for withdrawal of the blank from the support for its subsequent advancement along a predetermined path of travel.

2. In a high speed blank feeding mechanism for feeding narrow elongated strip blanks of sheet material, the combination of a magazine for holding a stack of strip blanks, said magazine having longitudinally spaced support members for holding said strip blanks against lateral displacement at one end thereof but permitting lateral movement of the blanks at an opposite free end thereof, a pair of high speed rotatable feed rollers disposed adjacent the free end of said support, and a reciprocable feed finger operable adjacent said magazine for individually and laterally shifting the free ends of said strip blanks from the stack of blanks, said finger also pivoting each blank at its retained end about a point disposed substantially in the plane of the bight of the feed rollers to bring the free end of each blank into between said rollers for successive withdrawal of the blanks from the magazine and for advancement along a predetermined path of travel.

3. In a high speed blank feeding mechanism for feeding narrow elongated strip blanks of sheet material, the combination of a magazine for retaining a plurality of strip blanks in stacked position, a pair of high speed rotatable feed rollers disposed adjacent one end of said magazine, and a short stroke reciprocable feed finger engageable with an edge of an individual strip blank intermediate its ends so as to pivotally shift the blank within said magazine about a point disposed substantially in the plane of the bight of the feed rollers to move a free end of the blank an increased distance to move said free end into between said rollers for withdrawal of the blanks from the magazine and for advancement along a predetermined path of travel.

4. In a high speed blank feeding mechanism for feeding narrow elongated strip blanks of sheet material, the combination of a magazine for retaining a stack of strip blanks and supporting the same at its opposite ends, a pair of high speed rotatable feed rollers disposed adjacent one end of said magazine, a short stroke reciprocable feed finger having a feed step engageable with an edge of an individual strip blank intermediate its ends

for pivoting the blank in said magazine about a point disposed substantially in the plane of the bight of the feed rollers to shift the blank into the bight of said rollers for withdrawal of the blank from the magazine, and a projection on said feed finger for engaging and moving said stack of blanks away from the blank being shifted to relieve the pressure thereon and to prevent scratching of the blank.

5. In a high speed blank feeding mechanism for feeding narrow elongated strip blanks of sheet material, the combination of a magazine for retaining and supporting a stack of strip blanks, a pair of separable normally open high speed rotatable feed rollers disposed adjacent one end of said magazine, means for laterally shifting one end of an individual blank in the stack to pivot the blank at its opposite end about a point disposed substantially in the plane of the bight of the feed rollers to bring the shifted blank end into position between said open feed rollers, and means operable in time with the shifting of said blanks for closing said rollers on the interposed end of a said blank for frictionally withdrawing the same from the magazine and for advancing it along a predetermined path of travel.

6. In a high speed blank feeding mechanism for feeding narrow elongated strip blanks of sheet material, the combination of a magazine for retaining and supporting at spaced localities a stack of strip blanks, a pair of high speed rotatable feed rollers disposed adjacent one end of the strip blanks in said magazine, and a reciprocable feed finger engageable with an edge of an individual strip blank for pivotally shifting the blank in said magazine about a point disposed substantially in the plane of the bight of the feed rollers to move the blank into the bight of said feed rollers for withdrawing the blank from the magazine, and stop means operable during abnormal conditions for holding said feed finger in an inoperative position and away from said stack of strip blanks to prevent feeding of the blanks from the magazine.

7. In a high speed blank feeding mechanism for feeding narrow elongated strip blanks of sheet material, the combination of a magazine for retaining and supporting at spaced localities a stack of strip blanks, a pair of high speed rotatable feed rollers disposed adjacent one end of the said magazine, a rocker lever disposed so as to have one end movable toward and away from said magazine, actuating devices for rocking said lever through a short rapid stroke, a feed finger carried

5 on said rocker lever and engageable with an edge of an individual strip blank for pivotally shifting the blank in said magazine about a point disposed substantially in the plane of the bight of the feed rollers to move said blank into the bight of said rollers for withdrawing the blank from the magazine, a spring latch engageable during abnormal conditions with said rocker lever for holding it and its feed finger in an inoperative position away from the stack of blanks to prevent feeding of the blanks from the magazine, and an electric solenoid operable against said latch for bringing it into holding engagement with said rocker lever.

8. In a high speed blank feeding mechanism for feeding narrow elongated strip blanks of sheet material, the combination of a magazine for retaining and supporting at spaced localities a stack of strip blanks in a horizontal position one above the other, guide rails disposed adjacent said magazine for supporting a supply of blanks to be fed to said magazine, a pair of high speed rotatable feed rollers disposed adjacent one end of said magazine, means for pivotally shifting an individual strip blank from said magazine about a point disposed substantially in the plane of the bight of the feed rollers to move said blank into between said rollers for withdrawal from the magazine, and a vibrating shoe engageable under said stack of blanks for raising and lowering the stack within the magazine in time with the feeding of the blanks therefrom to facilitate feeding of the blanks from said guide rails into the magazine.

9. In a high speed blank feeding mechanism for feeding narrow elongated strip blanks of sheet material, the combination of a magazine for retaining and supporting adjacent its opposite ends a stack of strip blanks, a pair of high speed rotatable feed rollers disposed adjacent one end of said magazine, a short stroke reciprocable feed finger disposed as to be engageable with an edge of an individual strip blank for pivotally shifting the blank in said magazine about a point disposed substantially in the plane of the bight of the feed rollers to move the blank into the bight of said rollers for withdrawal of the blank from the magazine, and a support element disposed against the opposite edges of the blanks in the stack adjacent the blank being shifted, said support element serving to back up and hold the stacked blanks against displacement relative to the blank being shifted.

RONALD E. J. NORDQUIST.
